UNITED STATES PATENT OFFICE

EDWIN SANFORD PHELPS, OF MONTCLAIR, NEW JERSEY

PROTECTOR-GUARD FOR STYLUS OF RECORDING MECHANISMS

Application filed April 2, 1931. Serial No. 527,258.

My invention relates to recording devices, and is particularly well adapted for use in connection with locks embodying means for making a record indicating the movement of the locking-bolt in the operation of locking and also unlocking the door to which the lock is applied so as to provide a record for the proprietor by which he may determine whether or not entrance has been effected during a period it is supposed entrance is not to be made. Various types of lock mechanisms for the purposes mentioned have been in practical use. In some of them there is employed a marking point or stylus in contact with a record-receiving member, such for instance as a sensitized-paper, to receive a record inscription of the period during which the lock-bolt has been in its locked-position and also in its unlocked position, and also of its movement from one of said conditions to the other condition. Said mechanism has afforded a large measure of safety in making the record desired. It has sometimes happened however that a dishonest employee, or other person, has tampered with the recording means, for instance, by breaking contact between the recording stylus and the record-receiving member, so that during the period immediately following such surreptitious manipulation the locking-bolt may be thrown and during that period no record made, and at the end of the period the stylus be reset to its recording position, and thus the proprietor of the place obtains a fictitious or false record and the dishonest individual is liable to escape detection. To guard against the possibility of making such false records is the primary purpose of the present invention. To that end I provide means designed to maintain constant record making contact between the stylus and record-receiving member so that a record will be made of a fraudulent manipulation of part of the record making instrumentalities as well as record of the legitimate operation of the instrumentalities, and thus the proprietor, or his representative, is better enabled to be informed of the unauthorized tampering or manipulation of the recording mechanism. In the preferred embodiment of this invention, I provide means

for guarding against breaking contact between the marking stylus and record-receiving member so that constant contact between them is maintained which results in making a record of both authorized and unauthorized movement of the locking bolt, and thus a factor of additional safety to the recording mechanism is provided.

In the accompanying drawings illustrating one embodiment of the invention,

Figure 1 is a front elevation of a casing containing recording mechanism, having a portion broken away to show a record-receiving member of an acceptable character, and a stylus for making a record thereon, and also showing the present invention applied to maintain constant recording contact between the stylus and record-receiving member;

Figure 2 is a top plan view showing the feature of the present invention and associated parts;

Figure 3 is a vertical section taken through the upper part of the record-containing casing;

Figure 4 is a detached, perspective view of the stylus protecting guard.

In the drawings the numeral 1 designates a casing in which is enclosed the recording mechanism, and in the lower part of which is a lock-bolt (not shown) operable by a key inserted in the lock-tumbler 2, or otherwise, for projecting and also retracting the bolt through proper connections not constituting the present invention and consequently not shown or described in detail. Access may be had to the interior of the casing through a hinged door 3, or otherwise. The numeral 4 designates a record-receiving member, which preferably consists of paper having a sensitized surface upon which a stylus will make a suitable recorded inscription. In the illustration given the record-receiving member is suitably connected to a member by which it may be progressively moved, which may be a dial-plate 5 mounted to rotate with a shaft 6 suitably mounted and rotated through a pinion 7 operatively connected with suitable clock-train deriving power from a spring-barrel, or otherwise, so as to move the

record-receiving member relatively to its marking stylus, the record-receiving paper being secured to the dial-plate by pins 7^a passing through the paper and by spring fingers 8 pressing against the paper and held by a threaded thumb nut 9. The marker or stylus 10 is carried by a swinging arm 11, preferably a spring arm, which holds the point of the marker or stylus in contact with the sensitized surface of the record receiving member, and with said arm is associated a finger 12 whose free end bears against the periphery of a snail 13 attached to one face of a toothed wheel 14 which derives rotative movement from the clock-train referred to so that the stylus will make successive convolute markings on the record receiving member as the latter is moved along and the stylus is moved progressively in a radial direction, under movement of the snail, over the record receiving member. The lock-bolt may be suitably connected with the swinging arm of the stylus so that when the bolt is projected in one direction the stylus arm will be swung so as to make a radial marking on the record-receiving member which read in connection with the time indicating markings indicated at A on the face of the record-receiving member will give the hour and fractional part of the hour when the bolt was projected; and when the bolt is retracted the swinging arm of the stylus will be swung inwardly under spring pressure or otherwise, and the stylus will make another marking on the record-receiving member which read in connection with the time divisions on the face of the paper will indicate the hour and fractional part of the hour at which the bolt was retracted. The parts so far generally referred to and their operation are old and well known and susceptible of more or less variations and do not constitute the present invention and therefore are not illustrated and described in more detail, and only so much of such parts are illustrated as necessary to understand the present invention.

Under constructions heretofore used it is possible to physically move the stylus from out of contact with the record-receiving member and then manipulate the bolt actuating means so as to throw the bolt without recording its movement and, after gaining access to the premises to which the recorder is applied, to restore the recording stylus to its operative position and thus the purposes of the unfaithful employee or other person, is made possible of accomplishment without detection or making a record easily read or deciphered. To protect the recording device against such nefarious practice, I have devised a protecting guard for the stylus which prevents the stylus from being moved out of contact with the record-receiving member so that the stylus must make a record under all conditions and thus afford positive evi-

dence or proof of any such unlawful or unauthorized tampering with the recorder. For that purpose I provide a guard positioned in such relation to the stylus that the guard will prevent such movement of the stylus as would break contact between it and the record-receiving member, with the result that the stylus must make a marking on the record-receiving member under all conditions. If the stylus should be moved so as to pass outside of or beyond the record receiving face, or boundary line, of the record-receiving member, the stylus will make a record on the record-receiving member throughout the length of travel of the stylus, and thus afford evidence of such unauthorized tampering with the recorder. The preferred form of the protecting guard is illustrated in Figure 4 of the drawings and preferably comprises a bracket 15 for attachment by a pin 16 and screw 17 to a suitable support and provided with a finger 18 to lie in the path of the longitudinal axis of the stylus, preferably across its outer end, as shown in Figs. 2 and 3 of the drawings, so that the marking point of the stylus will be prevented from being moved out of contact with the record-receiving member and thus will insure the making of a continuous inscription on the record-receiving member so long as the stylus and record-receiving member are in physical contact with each other in the operation of the recorder. Without such protecting guard the stylus could be moved outwardly away from the record-receiving member so as not to be in contact therewith and the swinging arm of the stylus could be swung so as to carry the stylus outside of the periphery or border line of the record-receiving member to a position outside of the area of the face of the record-receiving member without a record being made on the record-receiving member, during the period the stylus is out of its recording position, and the unfaithful employee, or other person, would be given an opportunity to enter the premises without making a record of the fact, and afforded an opportunity to cover up his action by restoring the stylus to its operative position after accomplishment of his purpose. But if continuous contact between the stylus and record-receiving member is insured, then an inscription is made on the record-receiving member in swinging the stylus to a position outside of the area or face of the record-receiving member, and attention thus called to such surreptitious manipulation of the recorder. Additional safety or security is accordingly afforded by the recorder as will be apparent from the foregoing description. The guard-member may be provided with a backing-plate 19 positioned to lie back of the record-receiving member as shown in Figures 2 and 3 so as to afford a stiff backing at the point where the

stylus makes contact with the record-receiving member, if such member be made of paper.

It will be observed that the protecting guard-plate extends or lies in the path of travel of the stylus so that throughout the travel of the stylus the guard-plate will prevent breaking contact between the stylus and record-receiving member so that throughout the travel of one of the recording instrumentalities relatively to the other contact will be maintained between the cooperating recording instrumentalities and a recorded inscription made upon the record-receiving member.

While in the particular embodiment of the invention illustrated, the record-receiving member is a rotating sensitized paper with which the stylus is held in constant contact in the recording operation it is obvious that the invention is not limited to that particular embodiment, and that the invention contemplates and includes within its scope other embodiments in which means are employed for maintaining substantially constant contact between the stylus and the record-receiving member during the record making period of the recorder.

Having described my invention and set forth its merits what I claim is:—

1. In a recording mechanism including a record-receiving member and a stylus for making an inscription thereon; a protecting-guard member disposed in relation to the stylus to prevent movement of the stylus in a direction breaking contact between its marking-point and the record-receiving member during the recording-period of the recorder.

2. In a recording mechanism including a record-receiving member and a stylus for making an inscription thereon; a protecting guard-member disposed in the path of travel of the stylus, in relation to the record-receiving member to prevent movement of the stylus in a direction breaking contact between its marking point and the record-receiving member in progressive movement of the stylus along its path of travel.

50 In testimony whereof I affix my signature.

EDWIN SANFORD PHELPS.
